R. B. KENDIG, DEC'D.

V. S. KENDIG, EXECUTRIX.

CAR TRUCK.

APPLICATION FILED AUG. 6, 1918.

1,289,807.

Patented Dec. 31, 1918.

Inventor:

Roscoe B. Kendig, Deceased
By Virginia S. Kendig, Executrix

By J. R. Cornwall, Atty.

UNITED STATES PATENT OFFICE.

ROSCOE B. KENDIG, DECEASED, LATE OF PORT CHESTER, NEW YORK, BY VIRGINIA S. KENDIG, EXECUTRIX, OF PORT CHESTER, NEW YORK.

CAR-TRUCK.

1,289,807.

Specification of Letters Patent. Patented Dec. 31, 1918.

Application filed August 6, 1918. Serial No. 248,571.

To all whom it may concern:

Be it known that ROSCOE B. KENDIG, late a citizen of the United States, residing at No. 1 Hawthorne Ave., Port Chester, New York, deceased, did invent certain new and useful Improvements in Car-Trucks, of which the following is a full, clear, and exact description, such as will enable others skilled in the art to which it appertains to make and use the same, reference being had to the accompanying drawings, forming part of this specification.

This invention relates generally to railway car truck construction and more particularly to a new and improved spring and equalizer arrangement for yieldingly supporting the truck frame upon the journal boxes.

The principal objects of this invention are, to arrange the springs and equalizers so that they will in no wise interfere with the free inspection, repair and adjustment of the brakes and brake rigging associated with the truck; further to provide guides for the journal boxes, so that the same are maintained in true vertical positions, free from physical contact with the pedestals except at such intervals when the brakes are applied, and further, to provide improved means for connecting the ends of the semi-elliptic springs and the rigid equalizers, such means preventing lateral displacement of the associated parts.

With the foregoing and other objects in view, this invention consists in certain novel features of construction and arrangement of parts, hereinafter more fully described and claimed, and illustrated in the accompanying drawings, in which—

Figure 1 is a plan view of the side portion of a six wheel truck frame with which the spring equalizer arrangement is associated;

Fig. 2 is a side elevational view of the truck frame with the spring and equalizer arrangement applied thereto;

Fig. 3 is an enlarged vertical section taken approximately on the line 3—3 of Fig. 2;

Fig. 4 is a detail view partly in section showing the end of one of the semi-elliptic springs positioned on the end of one of the rigid equalizers.

Referring by numerals to the accompanying drawings, 10 designates the wheel piece 55 of a truck frame, the latter being prefer-

ably of integral construction and provided with the usual pairs of pedestal jaws 11. Arranged between these pairs of pedestal jaws are journal boxes 12, the same containing the usual bearings for the ends of the wheel carrying axles 13.

The wheel pieces 10 are preferably hollow and of box-like construction in cross section, the bottom wall of each wheel piece being cut away at points between the pedestal jaws for the accommodation of the journal boxes as the same move upwardly during service. The outer wall of each wheel piece is cut away at suitable points to permit the ready insertion or removal of the rigid equalizer members and springs coöperating therewith.

Mounted on each journal box 12 is a block or bracket 14, preferably of cast metal, the same being substantially U-shape in cross section and serving as a support for one of the rigid equalizer members 15. These equalizer members are preferably cast and seated in said members at or near the center thereof is a transversely disposed pin 16, the end portions of which project beyond the sides of the equalizer and rest in suitable bearings 17, which latter are formed in the upper portions of the side walls of the block or bracket 14.

The outer wall of each block or bracket 14 is extended upwardly a short distance beyond the bearing for the pin 16 and the side edges of this upwardly projecting portion bears directly against the peripheries 90 of rollers 18, which latter are journaled on pins or bolts 19, the latter being seated in the outer wall of the wheel piece 10.

The side edges of the upwardly projecting portion of the block or bracket 14 are parallel so that as said block and the journal box supporting the same move vertically, said journal box is held to move in a true vertical position and without any tendency to rotate about the axle and thereby bind or bear with heavy pressure against the associated pedestal jaws.

The outer ends of the outer or end pair of rigid equalizers 15 are provided with hooks 20 which receive the upper ends of hangers 105 21, the latter extending downward through suitable bearings in the lower wall of the wheel piece and the lower ends of said hangers carrying disks 22. These disks serve as seats for compression springs 23, the 110

upper ends of which bear directly against the underside of the end portions of the wheel piece 10.

5 Bearing on the upper portion of the wheel piece and preferably against the underside of the top plate thereof are semi-elliptic springs 24, the same being disposed between the rigid equalizers and the ends of these springs bear directly upon both 10 ends of the middle equalizer and the inner ends of the outer or end pair of equalizers.

As illustrated in Fig. 4, the ends of the springs 24 are bifurcated as designated by 15 25 in order to receive lugs or tongues 26 which are formed on the ends of the equalizers 15. This particular construction maintains the ends of the springs 20 and equalizers 15 in proper assembled relation and prevents lateral displacement of the parts.

20 A spring and equalizer arrangement constructed as herein disclosed is yielding and resilient to a high degree and by providing 25 guiding means for the journal boxes while the same move vertically between the pedestal jaws, said boxes are normally maintained out of physical contact with said pedestal jaws, and they are effectually held 30 against tendency to rotate about the axles.

It will be readily understood that minor 35 changes in the size, form and construction of the various parts of this improved car truck can be made and substituted for those herein shown and described, without departing from the spirit of the invention, 40 the scope of which is set forth in the appended claims.

What is claimed is:

1. The combination with a car truck, its 45 journal boxes and pedestal jaws, of means for yieldingly supporting the car truck upon the journal boxes, and means independent of the pedestal jaws for guiding the journal boxes during their vertical movement, said means comprising rollers journaled on the truck frame above each journal box and a member extending upwardly from each

journal box and normally bearing against said rollers.

2. The combination with a car truck, its 50 journal boxes and pedestal jaws, of means for yieldingly supporting the car truck upon the journal boxes, and means independent of the pedestal jaws for normally holding the journal boxes out of physical contact with said jaws, said means comprising 55 rollers journaled on the truck frame above each journal box and a member extending upwardly from each journal box and normally bearing against said rollers.

3. The combination with a car truck, its 60 journal boxes and pedestal jaws, of equalizer means for yieldingly supporting the car truck upon the journal boxes, a member projecting upwardly from each journal box, which member supports a portion of the 65 equalizing means, and guiding rollers on the truck frame for each upwardly projecting member.

4. The combination with a car truck, its 70 journal boxes and pedestal jaws, of means for yieldingly supporting the car truck upon the journal boxes, an upwardly projecting member supported by each journal box, said member serving as a support for a part of the truck supporting means, and a 75 pair of guide rollers for each journal box supported member.

5. In a car truck, a wheel piece provided with pedestal jaws, a journal box positioned between said jaws and adapted to move vertically, a member carried by and projecting upwardly from said journal box into the wheel piece, and rollers journaled on said wheel piece, which rollers serve as bearings for the member projecting upwardly from the journal box.

In testimony whereof I hereunto affix my signature, this 16th day of July, 1918.

VIRGINIA S. KENDIG,
*Executrix of the last will and testament of
Roscoe B. Kendig, deceased.*
